UNITED STATES PATENT OFFICE.

ADOLPH VESTER, OF NORTH ATTLEBOROUGH, MASSACHUSETTS, AND JOHN BECKER, OF PAWTUCKET, RHODE ISLAND.

BRACELET.

SPECIFICATION forming part of Letters Patent No. 240,206, dated April 12, 1881.

Application filed February 5, 1881. (No model.)

To all whom it may concern:

Be it known that we, ADOLPH VESTER, of North Attleborough, in the county of Bristol and State of Massachusetts, and JOHN BECKER, 5 of Pawtucket, in the county of Providence and State of Rhode Island, have invented a new and useful Improvement in Bracelets, of which the following is a full, clear, and exact description.

10 Our invention relates to an improvement in the construction of bracelets; and the invention consists in joining two or more sections composed of wire twisted into various shapes by soldering, giving an appearance of a chain-bracelet.

15 The accompanying drawings represent various forms of constructing a bracelet according to our invention.

In Figure 1 are shown three sections, each 20 composed of two twisted wires, A A', and united by soldering at the points of contact 11. This bracelet is shown as provided with a spring, 3, to make it self-closing, and with a catch, 4, for uniting the free ends.

25 In Fig. 2 is shown a bracelet composed of four sections, each consisting of two strands of wire closely twisted and united by solder.

In Fig. 3 is shown a bracelet constructed of 30 two sections and soldered, forming a perfect imitation of a link chain.

The wire of which the sections are composed may be of any material commonly employed in the manufacture of jewelry.

Heretofore bracelets have been constructed of wire twisted and interlaced so as to form 35 a chain or link bracelet, and they have also been held by a bar or rod passing through the spirals and locking the adjoining sections together. This manner of constructing bracelets is necessarily expensive; and our purpose 40 is to simplify the construction while retaining the general appearance of this class of bracelet.

It is evident that the forms of bracelets may be varied indefinitely without departing from the spirit of our invention, the essential principle of which is the uniting of wire sections 45 by soldering.

We therefore claim—

A bracelet composed of two or more sections, the points of contact of which are united 50 by soldering, each section being composed of one or more strands of wire.

In testimony whereof we have signed our names to this specification in the presence of two subscribing witnesses.

ADOLPH VESTER.
JOHN BECKER.
